US0D1000918S

(12) **United States Design Patent** (10) **Patent No.:** **US D1,000,918 S**
(45) **Date of Patent:** **** Oct. 10, 2023**

(54) **LUNCH BOX**

(71) Applicant: **Ruoxi Gan**, Jiangyou (CN)

(72) Inventor: **Ruoxi Gan**, Jiangyou (CN)

(**) Term: **15 Years**

(21) Appl. No.: **29/889,305**

(22) Filed: **Apr. 11, 2023**

(51) LOC (14) Cl. **07-01**

(52) U.S. Cl.

USPC **D7/703; D7/629**

(58) **Field of Classification Search**

(57) **CLAIM**

The ornamental design for a lunch box, as shown and described.

DESCRIPTION

FIG. 1 is a perspective view of a lunch box showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is an exploded perspective view of the lunch box. The dash-dot broken lines in the drawings depict portions of the lunch box that form no part of the claimed design.

1 Claim, 10 Drawing Sheets
